ARTHUR JAMES TIZLEY, OF NEW YORK, N. Y., ASSIGNOR TO THE BRYANT ELECTRIC COMPANY, OF BRIDGEPORT, CONNECTICUT, A CORPORATION OF CONNECTICUT.

ELECTRIC-LAMP SWITCH.

1,181,046.

Specification of Letters Patent. Patented Apr. 25, 1916.

Application filed August 26, 1914. Serial No. 858,614.

To all whom it may concern:

Be it known that I, ARTHUR J. TIZLEY, a subject of the King of Great Britain, and a resident of the city of New York, borough of Brooklyn, in the county of Kings and State of New York, have invented a new and Improved Electric-Lamp Switch, of which the following is a full, clear, and exact description.

10 My invention has for its object to provide an electric lamp switch which may be disposed within a porcelain candle fixture of the ordinary construction and which may be operated from an end of the said porcelain candle fixture.

15 Other objects of the invention are to provide convenient means for operating the switch which will not impair the attractiveness of the fixture.

20 Additional objects of the invention will appear in the following specification in which the preferred form of my invention is described.

25 In the drawings similar characters of reference refer to similar parts in all the views, in which—

Figure 1 is a sectional view of a porcelain candle fixture, the switch being disposed within the porcelain candle; Fig. 2 is a 30 sectional view on the line 2—2 of Fig. 1; Fig. 3 is a sectional view showing one of the operating disks; Fig. 4 is a sectional view showing the other operating disk; Fig. 5 is a transverse sectional view showing the relationship of the two disks; and Fig. 6 is a sectional view showing another 35 operating means for the switch.

By referring to the drawings, it will be seen that the lamp wires 10 and 11 are disposed in a tube 12 and that to this tube 12 there is secured by a set screw 13 a disk 14 on which is disposed the porcelain candle 15, this porcelain candle 15 being of the usual construction. Within this porcelain 40 candle the lamp switch 16 is disposed. Mounted on the tube 12 there is a cap 17 and on this cap 17 there is disposed an insulating member 18, two conducting standards 19 being mounted on the insulating 45 member 18 and extending upwardly therefrom. The wire 10 is secured to the binding post 20 on one of the conducting standards 19, and the wire 11 is secured to the binding post 20 on the other standard 19. 50 Rotatably mounted on a horizontal axis

between the said standards 19 there is an insulating ratchet member 21, a conducting member 22 being mounted on the insulating ratchet member 21 and being in electrical engagement with one of the conducting standards 19, this conducting member 22 having portions 23 disposed over the alternate teeth of the insulating ratchet member 21, so that when the insulating ratchet member 21 is rotated the spring 60 contact member 24 will intermittently contact with the portions 23 of the conducting member 22. The resilient contact member 24 is mounted on the standard 25 which is supported by and extends upwardly from 65 the insulating member 18. Supported by the conducting standards 19 and 25 there is an insulating member 26, to the top of which there is secured a socket 30, the conducting standard 25 being in electrical 70 communication with the contact 28 at the center of the socket 27 by means of a conducting plate 29. The socket 30 is in electrical communication with the conducting standard 19 by means of the terminal 31 75 and the screw 32, which screw holds the top of the other conducting standard 19 in position.

As has been stated, the insulating ratchet member 21 is disposed between the conducting standards 19 and is mounted on a horizontal axis. Members 33 and 34 which are mounted in bearings in the conducting standards 19 serve to hold the insulating ratchet member 21 in position. The members 33 and 34 are insulated from each other by means of the ratchet member 21. A ratchet plate 35 is secured to the ratchet member 21 and a companion ratchet plate 36 is secured to a plate 37 mounted for rotating on the member 34. The plate 37 is held yieldingly with its shoulder 38 disposed against the stop 39 by means of a spring 40 passed around the member 34 having its terminal 41 secured to the plate 100 37 and its terminal 42 secured to the standard 19 adjacent the member 34. It will therefore be seen that when the plate 37 is rotated it will by means of the ratchet plate 36 rotate the ratchet plate 35 and with it 105 the insulating member 21 to move the teeth of the ratchet member 21 relatively to the spring contact member 24. A normal rotary movement of the ratchet member 21 will bring the resilient contact member 24 110

against the periphery of the ratchet member 21 beyond an adjacent tooth, and as the alternate teeth of the ratchet member 21 have portions of the conducting member 22 disposed thereover it will be understood that when the resilient contact member 24 comes in contact with the periphery of alternate teeth of the ratchet member 21 the circuit will be closed between the conducting standard 19 adjacent the conducting member 22 and the conducting standard 25. A flexible member 43 of any suitable character is secured to the plate 37, preferably in a channel 44, and this flexible member 43 is led down through an opening 45 in the insulating member 18 and through an opening 46 in the cap 17, the flexible member 43 being then disposed through an orifice 47 in the disk 14.

Disposed below the disk 14 for rotating relatively thereto on the tube 12 there is a disk 48 which has an annular channel 49 in which there are ribs 50. The terminal of the flexible member 43 is enlarged as shown at 51 and this enlarged terminal is disposed in the channel 49 to be engaged by one of the ribs 50. When the terminal 51 is thus engaged by one of the ribs 50 and the disk 48 is rotated by means of a collar 52 to which it is secured, the terminal 51 will be rotated until it reaches one of the recesses 53 in the disk 14, when the terminal 51 will enter the said recess 53 thereby permitting the rib 50 to pass. When the rib 50 passes the enlarged terminal 51 of the flexible member 43 the flexible member 43 with its terminal 51 will move back to normal position as shown in Fig. 1 of the drawings, the spring 40 serving to rotate the plate 37 to bring the parts back to the said position.

In the modified form of the invention shown in Fig. 6 of the drawings, the porcelain candle fixture 15^a is mounted directly on a base collar 54 which has an opening 55 near its lower end through which the flexible member 43 is disposed, said flexible member 43 having an enlarged terminal 51^a which may be drawn down by the user to operate the switch which has been described in this specification.

Having thus described my invention, I claim as new and desire to secure by Letters Patent:

1. A candelabra switch comprising a tubular wire conduit, an insulating switch body mounted at one end of said conduit, a hollow candelabra body incasing said switch and wire conduit, a rotary switch member mounted on an axis extending transversely of the candelabra body and means for operating the rotary switch, said means extending between the wire conduit and candelabra body to one end of the latter.

2. A candelabra switch comprising a tubular wire conduit, an insulating switch body mounted at one end of said conduit, a hollow candelabra body incasing said switch and wire conduit, a rotary switch member mounted on an axis extending transversely of the candelabra body and means for operating the rotary switch, said means extending between the wire conduit and candelabra body to one end of the latter, in combination with a lamp socket mounted on said insulating switch body substantially in line with the wire conduit but at the opposite end of the switch body therefrom.

3. In an electric lamp switch, two conducting standards, an insulating ratchet member rotatably mounted on an axis extending from one of the conducting standards to the other, a conducting member mounted on the ratchet member and having extensions spaced apart over the ratchet teeth, the conducting member contacting with one of the conducting standards, a third conducting standard, a resilient contact member mounted on the third conducting standard and engaging the ratchet teeth for contacting with the first conducting member, and means for rotating the ratchet member.

4. In an electric lamp switch, a pair of wire terminal standards permanently insulated from each other, a rotary switch piece supported by said standards, said rotary switch piece comprising an insulating body with peripheral ratchet teeth and a conducting strap having portions overlying certain of said teeth and electrically connected to one of said standards, in combination with a stationary spring contact engaging the ratchet face of the rotary switch member, ratchet means on the axis of the switch piece for rotating the latter, a pair of lamp socket terminals, a constant connection to one of said socket terminals through one of the switch standards and an interrupted connection to the other socket terminal through said switch piece and spring contact from the other standard, substantially as described.

5. In an electric lamp socket, a switch body comprising a pair of buttons of insulating material, three standards spacing said buttons apart, two of said standards being opposed and permanently insulated from each other and constituting wire terminals, a rotary switch piece supported between said opposed standards and comprising an insulating body having peripheral ratchet teeth and a conducting strap having portions overlying certain of said ratchet teeth, said strap being electrically connected to one of said standards, a spring contact supported by the third standard and bearing upon the ratchet face of said switch piece,

- in combination with ratchet means on the axis of said switch piece for rotating the latter, substantially as described.
6. In an electric lamp switch, an elongated member, a rotary switch member mounted within the elongated member on an axis extending transversely thereof, flexible means for operating the rotary switch member, and rotatable means mounted beneath and substantially co-axially with the elongated member for operating the flexible means.
7. In an electric lamp switch, a rotary switch member, a flexible means having an enlarged member for operating the rotary switch member, a disk having an opening through which the enlarged member on the flexible means is disposed, a second disk for rotating against the first disk and having an annular channel in which the enlarged member is disposed, a rib disposed in the channel to prevent the enlarged member from passing the rib under normal conditions, and a recess in the first plate spaced from the opening to permit the enlarged member to pass the rib.
8. An electric lamp switch, a switch-operating means consisting of a plate having an opening through which an enlarged member on a flexible means is normally disposed, a second disk for rotating against the first disk and having an annular channel in which the enlarged member is disposed, a rib in the channel to prevent the enlarged member from passing the rib under normal conditions, and a recess in the first disk spaced from the opening to permit the enlarged member to pass the rib.
9. In an electric lamp switch, a rotary switch member, an oscillatory member having an operative connection therewith, a spring constantly tending to rotate said oscillatory member in one direction, a flexible pull member for moving said oscillatory member in the opposite direction against the action of said spring, an escapement plate through which said flexible member passes, a movable plate facing said stationary plate, an element on said flexible pull member engaged between said movable and stationary plate and a recess in said stationary plate permitting the escape of said element under the influence of said spring after the displacement of the flexible member a predetermined distance, for the purpose described.
10. In an electric lamp switch, an elongated member, a rotary switch member disposed in and mounted on an axis extending transversely of the elongated member, a flexible means having an enlarged member, 60 for operating the rotary switch member, a disk having an opening through which the enlarged member on the flexible means is disposed, a second disk for rotating against the first disk and having an annular channel in which the enlarged member is disposed, a rib disposed in the channel to prevent the enlarged member from passing the rib under normal conditions, and a recess in the first disk spaced from the opening to 70 permit the enlarged member to pass the rib and a spring to retract said flexible means after said member has escaped the rib.
11. A candelabra socket comprising a tubular wire conduit, an insulating switch body mounted at one end thereof, socket terminals mounted on said switch body in extension of the wire conduit, a candelabra casing inclosing said switch and wire conduit and a flexible switch-operating member 80 arranged within said candelabra casing and concealed thereby, substantially as described.
12. An electric switch comprising a flexible operating member, a stationary guide to which the end of said flexible member passes, 85 a rotary member juxtaposed to said stationary member and having means for temporarily engaging said flexible member, together with means for breaking said engagement after a predetermined extent of 90 rotation of said rotary member with relation to the stationary member, for the purpose described.
13. In an electric switch a flexible pull member, a rotary engaging member having 95 unlimited freedom of travel in one direction, a stationary member associated therewith, means at a plurality of points on said rotary member for engaging said flexible member and means breaking said engagement after a predetermined extent of engaged 100 travel to free said flexible member, for the purpose described.
14. In an electric switch, a flexible operating member, a stationary member and 105 a movable member between which said flexible member is engaged and means for breaking the engagement of said flexible member after a predetermined extent of travel of the movable member with relation to the stationary member, for the purpose described.
- In testimony whereof I have signed my name to this specification in the presence of two subscribing witnesses.

ARTHUR J. TIZLEY.
